UNITED STATES PATENT OFFICE.

KEMP B. ARTHUR, OF NORFOLK, VIRGINIA.

ADJUSTABLE AND SEPARABLE STUD OR BUTTON.

1,349,649.

Specification of Letters Patent. Patented Aug. 17, 1920.

Application filed December 10, 1919. Serial No. 343,768.

To all whom it may concern:

Be it known that I, KEMP B. ARTHUR, a citizen of the United States, residing at Norfolk, in the county of Norfolk and State 5 of Virginia, have invented certain new and useful Improvements in Adjustable and Separable Studs or Buttons, of which the following is a specification, reference being had to the accompanying drawings.

10 This invention relates to fastening devices, and particularly to fastening devices in the nature of studs or buttons, and the general object of the invention is to provide a fastening device of this nature formed of two 15 parts which are adjustable toward or from each other so as to adjust the length of the stud or button.

A further object is to provide a construction of this character wherein the two parts 20 of the stud or button may be formed so as to be entirely detachable from each other, or so as to be only adjustable upon each other but not detachable.

More specifically speaking, one of the objects of the invention is to provide a button 25 which may be used as a collar button, shirt stud, cuff button, or the like which is so constructed that it may be shortened for use, for instance, as a stud or for use as a back 30 collar button, or lengthened for use as a front collar button or, if used as a cuff button, can be adjusted so as to be used with stiff cuffs or with soft cuffs where there are a plurality of plies and the button has to be 35 relatively long.

Other objects will appear in the course of the following description.

My invention is illustrated in the accompanying drawings, wherein:—

40 Figure 1 is an elevation of an adjustable fastener constructed in accordance with my invention, the female member being partly in section;

Fig. 2 is a section on the line 2—2 of 45 Fig. 1;

Fig. 3 is an elevation of the construction shown in Fig. 1;

Fig. 4 is a fragmentary sectional view of a slightly modified form of fastener;

50 Fig. 5 is a longitudinal sectional view of a "sample button," that is a button for holding samples together.

Referring to these drawings, it will be seen that my button or fastener comprises 55 two members designated A and B. The member A is a male member and comprises

the base 10 with the cylindrical shank 11 which is somewhat rounded or tapered at its extremity. The female member B has a head 12 and a hollow, cylindrical shank 13. 60 The stem 11 is formed with diametrically opposed, longitudinally extending grooves 14 and with a plurality of circumferentially extending grooves 15 disposed at equal distances along the shank. There are two series 65 of these grooves 15, one series intersecting and extending from one of the grooves 14 and the other intersecting with and extending from the other groove 14. The grooves 15, as illustrated in the sectional view in 70 Fig. 2, become gradually less in depth from the point of intersection of the grooves 15 with the corresponding groove 14. This is illustrated on an exaggerated scale in Fig. 2. The hollow stem 13 into which the stem 75 11 fits is formed with two diametrically opposed, inwardly projecting studs 16 which are adapted to engage in the grooves 14 and also with two inwardly protuberant studs 17 which are disposed intermediate between 80 the studs 16. These inward protuberances or studs 16 and 17 may be formed by punching in the material of the cylindrical shell 13 by means of a prick punch or other like device. 85

In putting these two sections together and adjusting them, the stem 11 is inserted in the cylindrical stem 13, the members A and B being so adjusted with relation to each other that the studs 16 will enter the 90 grooves 14. When this is the case, the two sections A and B may be forced toward each other, the stud 16 traveling in the grooves 14 and preventing any relative rotation of the two sections until the studs 16 95 aline with any pair of the circumferential grooves 15. The studs 17 will obviously, under these circumstances, not aline with the grooves 14, but will travel over the face of the stem 11 and when they meet grooves 100 15, the studs will spring into these grooves, giving a slight clicking sound which will notify the user that the studs have reached one pair of the grooves 15. Then and only then can the members A and B be relatively 105 rotated. If the member B is rotated to the left in Fig. 2, the studs 16 will ride along one side of the circumferential grooves 15 and the upwardly inclined bottoms of these grooves will gradually cause these studs to 110 bind upon the shank 11 until the two parts become locked by contraction in their ad-

justed positions, thus holding the two parts of the sections A and B of the stud or button in their adjusted position.

By providing the stud 17, it is an easy matter for a person to adjust the button without looking at it, as because of the clicking sound made by the springing of the stud 17 into the grooves 15, the user will know when the sections have been so 10 adjusted as to bring the studs 16 and 17 into alinement with any one of the series of circumferential grooves 15 and can then relatively turn the two sections to lock them together.

15 I do not wish to be limited to any particular form of button or fastening device, as my invention is equally applicable to large buttons or to small buttons. The device, as before explained, is particularly adapted to 20 the construction of collar buttons, as it permits a single collar button to be adjusted for use either as a relatively long front collar button or relatively shorter rear collar button, or a relatively short stud. The device, however, may be used as fasteners for 25 curtains, as a means for holding together a plurality of plies of fabric, and obviously the device may be made of various sizes for different purposes. The device may be 30 used for holding the curtains of automobiles and motor boats, carriage curtains, for draperies, for holding samples together, and in fine for many different uses which will be obvious. It is also obvious that the device may be made of various metals, gold, 35 silver, aluminum, or brass, and that it may have a more or less ornamental form or design.

Under some circumstances, it is not desirable to have the two sections A and B entirely detachable, and in this case, as illustrated in Fig. 4, the grooves 14 do not extend to the extremity of the shank 11 but terminate short of the extremity. Then the 40 depressions or studs 16 are formed after the shell 13 is slipped over the stem 11. In that case the studs 16 cannot move beyond the extremity of the grooves 14, and therefore the two sections cannot be detached 45 from each other.

50 It will be noted that the tapering portion of the shank 11 of section A permits it to be readily inserted through a button hole, and inasmuch as the extremity of the shank 11 is tapered, the parts of the button may be readily engaged with each other.

55 In Fig. 5, I show my invention as applied to a sample button, that is a button designed to hold samples together, though the button might also be used for holding other parts together, as for instance, layers 60 of leather or paper. In this form of my device, the section A' is constructed substantially like the section A previously described except that the shank 11^a is pointed, 65 as at 18. The section B' operates in a simi-

lar manner to the section B, except that this section B' has the bore of the sleeve 13^a extending entirely through the head or base 12^a. It will be understood that the shank 11^a is to be formed with the longitudinal 70 grooves 14^a and the circumferential grooves 15^a, and that the sleeve 13^a is to be provided with the depressions 16^a and 17^a. In other words, the button has exactly the same form as heretofore described, except that it is 75 modified slightly for its use as a means for fastening together samples or other layers of material, and the sleeve 13^a is relatively short in comparison with the form of button shown in Figs. 1 to 4. With this construction, the member B' can be slipped up and down on the grooved post 11^a and thus the sleeve may be disposed either adjacent the extremity of the shank or disposed at the base of the shank. By pointing the shank, 80 it may be readily forced through samples of material or through sheets of paper, or any other object to which the button is to be attached, and the head of the button disposed any desired distance from the base. 85

I claim:—

1. An adjustable fastener of the character described comprising two sections, one having a cylindrical stem and the other having a cylindrical sleeve fitting over the stem, the 95 stem being formed with a plurality of longitudinally extending grooves and with a plurality of circumferential grooves extending circumferentially from the longitudinal grooves, the sleeve having inwardly projecting 100 studs engaging said grooves.

2. An adjustable fastener of the character described comprising two sections, one having a cylindrical stem and the other having a cylindrical sleeve fitting over the stem, the 105 stem being formed with a plurality of longitudinally extending grooves and with a plurality of circumferential grooves extending circumferentially from the longitudinal 110 grooves, the sleeve having inwardly projecting studs engaging said grooves, said circumferential grooves becoming gradually shallower in depth as they extend away from the longitudinal groove whereby to cause the studs to bind within said circumferential grooves upon a relative rotation of the two sections.

3. An adjustable fastener of the character described comprising two sections, one having a cylindrical sleeve fitting over the stem, the stem being formed with a plurality of longitudinally extending grooves and with a plurality of circumferential grooves extending circumferentially from the longitudinal 125 grooves, the sleeve having inwardly projecting studs engaging said grooves, the socket being also formed with inwardly extending studs shallower than the studs which engage the longitudinal groove and adapted to ride 130

over the face of the stem and to spring into the circumferential grooves as the sections are shifted longitudinally on each other to thereby indicate the degree to which said sections have been shifted.

4. An adjustable and separable fastener consisting of two sections, one of the sections having a cylindrical stem and the other a cylindrical, tubular sleeve to receive the stem, the stem being formed with a longitudinally extending groove extending inward from the extremity of the stem and with a plurality of circumferential grooves extending from the longitudinal groove and each becoming gradually shallower in depth from its point of intersection with the longitudinal groove, the sleeve having an inwardly extending stud adapted to engage in said longitudinal groove to permit the longitudinal shifting of the sections upon each other and engage in the circumferential groove to permit the rotation of said sections upon each other, the sleeve being also

formed with a stud adapted to slip over the surface of the stem and snap into said circumferential groove to thereby indicate when the studs are in line with one of the circumferential grooves.

5. An adjustable fastener of the character described comprising two sections, one having a cylindrical stem or tongue, and the other having a cylindrical sleeve fitting over the stem, the stem being formed with a plurality of longitudinally extending grooves and with a plurality of circumferential grooves extending circumferentially from the longitudinal grooves, the sleeve having inwardly projecting studs engaging said grooves, each of said sections having a head, and the sleeved section having its bore extending entirely through the head, the shank or stem being pointed.

In testimony whereof I hereunto affix my signature.

KEMP B. ARTHUR.
